UNITED STATES PATENT OFFICE.

LEWIS T. RHOADES, OF MONT CLARE, PENNSYLVANIA, ASSIGNOR TO NEW YORK COIL COMPANY, INCORPORATED, OF NEW YORK, N. Y.

CIRCUIT-BREAKER.

1,260,809.

Specification of Letters Patent. Patented Mar. 26, 1918.

Application filed September 25, 1917. Serial No. 193,065.

To all whom it may concern:

Be it known that I, LEWIS T. RHOADES, a citizen of the United States, residing at Mont Clare, in the county of Montgomery and State of Pennsylvania, have invented 5 certain new and useful Improvements in Circuit-Breakers, of which the following is a specification.

My invention consists of an improved circuit breaker which employs both mechanical and magnetic means to interrupt the current through the induction coil for the purpose of rendering certain and reliable ignition at all times in any type of internal combustion 15 engine.

It is a well known fact that when a magnetically operated vibrator or circuit breaker is employed in connection with a conventional spark coil, contact points very often 20 fuse or weld together, seriously interfering, or entirely preventing the production of a spark. When a magnetically operated circuit breaker is employed in conjunction with a plurality of coils which apparatus is commonly 25 called a "master vibrator," this welding or sticking action is practically unavoidable as the work which the contact point is required to perform is proportionate to the number of coils used. Furthermore, 30 in all magneto generators, in which no provision is made to cause the break of the contact points at a pre-determined position in relation to the armature's position with the permanent magnets, some form of 35 magnetic circuit breaker is necessary to insure the positive breaking of the circuit.

Heretofore, a number of conventional spark coils with two windings employing a magnetic vibrator, or a high tension distributor operating a number of cylinders in connection with one vibrating coil has been employed. In either instance, the uncertainty of the vibrator's action has always 40 been a source of trouble.

One object of my improved circuit operating mechanism is to entirely eliminate all such uncertainty of action and to provide a construction which will have comparatively few parts, which will be operative to 45 insure the production of an energetic spark at the proper time and at the proper position of the piston's travel at all times.

A further object of my invention is to produce a device in which the contact points 50 are always separated except at the time

when the coil is producing sparks. This is of great importance because it is well known that after an engine has stopped, the contact points are sometimes heated to a point sufficient to allow them to weld or stick together, 60 making it difficult or impossible to start the engine upon which such devices are attached.

It will be understood that in my improved construction that not only are the contacts normally separated, allowing cooling of the same, but also that positive mechanical means operates to forcibly separate these contacts. I therefore desire to lay great stress on the importance of the combination of the magnetic and mechanical circuit breaker which I employ and the connection of the magnet to the mechanical circuit breaker. 70

Furthermore, those skilled in the art are aware that in untimed magnetos of the so-called inductor type, there are just as many neutral positions, at which no current is generated, as there are coils to produce waves of alternating current. 75

By employing a circuit breaker constructed in accordance with my invention including a magnet, as the current starts to build up from zero, the magnet will cause the contacts to separate several times before the peak of the wave is reached, and also as the current recedes to zero and is again repeated in the next alternation, thus insuring proper ignition. Whereas, if a conventional "make-and-break" timer or distributor were attempted to be used, it is evident that should 80 the break occur at any of the neutral positions, no spark would be produced and ignition would fail. 90

The above mentioned objects and other advantageous ends which will be described 95 hereinafter, I attain in the following manner, reference being had to the accompanying drawings in which—

Figure 1 is a top plan view of my improved circuit breaker as adapted for use 100 in connection with an internal combustion engine, the apparatus being in a position which it assumes when the sparks are being produced under the influence of an electromagnet.

Fig. 2 is a front elevation of Fig. 1 with the wiring diagram omitted. 105

Fig. 3 is a side view of Fig. 2.

Fig. 4 is a top plan view of similar nature to Fig. 2 with the wiring diagram 110

omitted and showing the parts in the position which they assume when no sparks are being produced, the contacts having been separated by automatic and mechanical means.

Fig. 5 is a perspective view of certain of the elements of my invention which are movable to effect the "make-and-break" of the circuit.

10 Fig. 6 is a perspective view of the electro-magnet and the mounting thereof.

Fig. 7 is a fragmentary section taken on the line 7—7 of Fig. 1 showing a portion of the magnet support acting to prevent longitudinal movement of a cam shaft which forms a part of my invention.

Referring to the drawings, 1 represents a metallic base having a suitable bearing 2 for a rotatable shaft 3 which, in the present instance, will be considered to be rotated by a movable part of an internal combustion engine and in which certain rotatable positions of this shaft will correspond to explosive positions of the cylinders within the engine. A cam 4 is secured to the upper end of the shaft 3 and has operating portions 4^a thereon, there being as many portions 4^a as there are cylinders to the engine. As illustrated, there are four portions 4^a representing that the engine under consideration has four cylinders.

An electro-magnet 5 is mounted on an iron bracket 6. This bracket as clearly shown in Fig. 6, has a standard 7 which is connected to the rear end of the core 8 and is bent forwardly providing a plate 9. The forward end of this plate is positioned directly below the forward end of the core 8 and actually forms a second magnetic pole 25 for assisting in attracting an armature as will be more fully explained hereinafter.

A post 10 in the form of a metallic angle, has an extension 11 which rests upon the metallic base 1, and a standard section 12. The extension 11 has a hole 13 through which is inserted a pivot screw 14. This extension also has a slot 15 through which extends a screw 16.

The slot 15 is preferably made concentric 50 with the axis of the pivot screw 14 so that by loosening the screws 14 and 16, the post 10 can be moved into various pivotal positions and afterward secured to the base 1.

The standard 12 of the post 10 has secured to it by screws 17, a flat spring 18. To the free end of this spring 18, is secured a plate 19 which serves as an armature and has its end portion 20 in front of the electro-magnet 5. A cleat 21 is secured to the front 60 face of the plate 20 by a rivet 22, and this cleat has a lip 21^a which is spaced in front of the plate 19 as clearly shown in Figs. 1, 3, and 5.

A contact arm 23, preferably made of flat 65 spring steel, has its end 24 secured to the

spring 8 and its opposite end 25 adapted to vibrate between the lip 21^a of the cleat 21 and the outer surface of the plate 19. The plate 19, at its rear face, has secured to it an extension 26 which is preferably made of sheet iron, this extension at its bottom being positioned immediately in front of the forward end of the plate 9 which forms the support for the electro-magnet 5. This extension 26 also has a finger 27 which is 70 spaced from the rear surface of the plate 19 (see Figs. 1, 3, and 5) for a purpose herein-after to be described.

The contact arm 23 has a contact lug 28 which is adapted at certain times to engage 80 a contact screw 29 adjustably mounted on a post 30 which is positioned on the top of the base plate 1 but insulated therefrom. This post is electrically connected "in series" by a wire 31 with the electro-magnet 5 which in 85 turn is connected by a wire 32 through the medium of a primary coil 33, battery, or generator 34 to a ground 35, said wire 32 also being in connection with a condenser 35 and ground 36 as is one of the well known 90 forms of wiring.

It will be considered that the plate 1 is also grounded and thereby completes the circuit with the battery 34 and generator. The secondary coil 37 may be connected 95 either to a spark plug or to a distributor to effect the explosions in the cylinders.

The opposite face of the standard 12 of the post 10 has secured to it a flat spring plate 38 of greater strength than the spring 18. This plate 38 has a finger 39 secured thereto, said finger having a swell portion 40 designed to be engaged by the portions 4^a of the cam 4. The end 41 of the finger 39 is positioned in the space between the finger 17 and the plate 19. The tension of the spring plate 38 normally tends to move the armature plate 19 and contact arm 23 into such position that contact point 28 will contact with the contacting spring 29 to 105 close the circuit and thereby energize the magnet 5.

When the magnet 5 is energized, it attracts the armature plate 19 and this movement of the armature plate 19 causes the lip 21^a to kick the lug 28 away from the contact screw 29 and thereby break the circuit. This breaking action is done against the tension of the spring 18 and therefore as soon as the magnet becomes deenergized by the 115 breaking of the contact, the spring 18 will move the lug 28 again into engagement with the contacting screw 29. The making and breaking of the circuit in this manner causes a series of sparks to be produced.

As illustrated in Fig. 1, the parts are in a position to permit the make and break of the circuit as above described, and it will be noted that one of the portions 4^a is in engagement with the swell 40 of the finger 120

39 and the end 41 of this finger 39 is held out of engagement with the finger 27 against the tension of the spring 38. Thus, the armature plate 39 is free to vibrate to create 5 proper ignition during the explosion of one of the cylinders of the internal combustion engine which causes a movement of the shaft 3 due to the action of the engine, and thereby moves the cam into such position as to 10 free the swell 40 of the finger 39.

The action of the spring 38 upon the release of the finger 39 by the cam 4 is to strike and move the finger 27 and extension 26 toward the magnet 5, and since the extension 15 26, plate 19, and lip 21^a are all connected together, the lip 21^a will pull the contact arm and lug 28 out of engagement with the contact screw 29. This absolutely insures the separation of the contact lug 28 and the contact screw 29 after each ignition. This position is clearly shown in Fig. 4.

The continued turning of the shaft 3 will cause another portion 4^a of the cam 3 to move the finger 39 out of engagement with 25 the finger 27. The spring 18 will then tend to move the armature plate 19 into its normal position so that the lug 28 will engage the contact screw 29, thus the armature will be vibrated due to the make and break of 30 the current through the electro-magnet 5 and by the action of the spring plate 18. This action will continue until the cam 4 releases the finger 39, when the lug 28 and contact 29 will be separated as above described.

35 The plate 9 which forms the support for the magnet and also serves as an additional pole, is adapted to extend within a groove 42 in the shaft 3. Thus, the plate 9 serves as a key to prevent longitudinal movement 40 of the shaft 3.

It will thus be noted that my invention includes in combination, magnetically operated means for making and breaking the circuit for the production of the ignition 45 sparks and mechanical means, namely, the cam 4, finger 39, and spring 38 which insures the breaking of the circuit after the magnetic means has ceased its operation or during the dwell between the explosions of the 50 cylinders.

Furthermore, it will be understood that a part of the mechanical means, namely, the cam 4, also serves as a timer for determining the operation of the magnetic means by releasing the armature 19 to the control of the spring 18, so that the ignition takes place at the proper time with respect to the cylinders. Thus, my invention presents the advantage of having the ignition under the 55 control of a magnet and includes positive mechanically operated means for insuring the breaking of the contacts at the proper time and to prevent fusion which it is impossible to prevent when only the magnetic 60 action is depended upon.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims. 70

Having thus described my invention, what 75 I claim as new and desire to secure by Letters Patent is:

1. A circuit breaker including an electro-magnet, resilient means normally operative to close the circuit through the magnet to 80 effect the breaking of said circuit after which the circuit is both made and broken alternately by said resilient means and said magnet, mechanically operated means, and additional resilient means normally held under 85 tension by said mechanical means, said mechanical means being movable to periodically release the tension on said latter resilient means, said latter mentioned resilient means being of sufficient strength that when 90 thus released it will spring toward its normal position and in so doing will move said first resilient means to break and hold open the electric circuit, substantially as described. 95

2. A circuit breaker including means automatically operative to close the circuit, magnetic means operative against the action of said first means to break the circuit, means operative to move and normally hold said 100 first means to break the circuit independently of said magnetic means, and power driven mechanical means periodically operative to move said third mentioned means to permit the first-mentioned means to render 105 the magnetic means operative, substantially as described.

3. A circuit breaker including an electro-magnet, a contact member in circuit with the magnet, resiliently mounted means forming 110 an armature for the magnet and adapted to normally form contact with said member to close the circuit through said magnet thereby causing the attraction of the armature by the magnet to break the contact between the 115 resiliently mounted means and said member, a second resilient means normally operative to move said first means out of contact with said member to break the circuit independently of said magnet, and mechanical means 120 for moving and holding said second resilient means out of engagement with said first means thereby permitting the latter to contact with said member, substantially as described. 125

4. A circuit breaker including an electro-magnet, a contact member in circuit with the magnet, resiliently mounted means forming an armature for the magnet and adapted to normally form contact with said member to 130

- close the circuit through said magnet thereby causing the attraction of the armature by the magnet to break the contact between the resiliently mounted means and said member, 5 a second resilient means normally operative to move said first means out of contact with said member to break the circuit independently of said magnet, and a cam operative to move and hold said second means to free 10 said first means and permit the latter to move into contact with said member, substantially as described.
5. A circuit breaker including a supporting structure, an electro-magnet, a contact member in circuit with the magnet, a spring secured to said supporting structure and having a portion free to vibrate, an armature on said portion and adapted to be attracted by said magnet, contacting means 15 normally moved by said spring into engagement with said member to close the circuit through the magnet, a second spring secured to said supporting structure and having a finger thereon free to vibrate, a second finger 20 connected to said armature and having a portion spaced therefrom, said second spring being of greater strength than the first spring and normally movable into a position to move said contacting means out of engagement with the contact member by engaging and moving said second finger, and mechanical means operative to move said first finger against the action of its spring 25 into a position between the second finger and the armature permitting the latter to be moved by its spring into contact with the contact member to complete the circuit and to be moved by said magnet to break the circuit, said mechanical means being operative 30 after a pre-determined time to free the first finger and to permit its spring to move the contacting means out of contact with the contact member independently of the magnet and against the action of said first spring, substantially as described.
- 45 6. A circuit breaker including an electro-magnet, a contact member, a supporting structure, a post pivotally mounted on said supporting structure and having a slot 50 therein, binding means extending through said slot into the supporting structure whereby the post can be adjusted in various pivotal positions, an armature supported by said post and having contacting means for 55 engagement with the contact member, substantially as described.
7. A circuit breaker including an electro-magnet, a contact member, a supporting structure, a post pivotally mounted on said
- supporting structure, a spring secured to 60 said post and having an armature free to vibrate thereon, contacting means supported by said spring and adapted to normally engage said contact member due to the action of said spring, a finger carried by said armature 65 and having a portion spaced therefrom, a second spring supported on said post and having a finger thereon free to vibrate between the first-mentioned finger and the armature, and normally operative by its 70 spring to engage said first finger and thereby move said contacting means out of engagement with the contact member against the action of the first-mentioned spring, and mechanical means adapted to move said second-mentioned finger against the tension of its spring to free said first finger and permit the first-mentioned spring to move the contacting means into engagement with the contact member, substantially as described. 75
8. The combination of a supporting structure, a shaft rotatable therein and having a groove, a plate secured to said supporting structure and having a portion extending into said groove to prevent longitudinal 80 movement of the shaft, a magnet supported by said plate, an armature resiliently supported adjacent said magnet and having contacting means movable in conjunction therewith, a contact member in circuit with 85 said magnet, a resiliently mounted finger adapted to move said armature to separate the contacting means from the contact member, and means carried by said shaft for moving said finger into a position to release 90 said armature and permit it to move due to its resilient mounting to bring said contacting means into engagement with the contact member, substantially as described. 95
9. A circuit breaker including means 100 automatically operative to close the circuit, magnetic means operative against the action of said first means to break the circuit, resilient means automatically operative to move and normally hold said first means to break 105 the circuit independently of said magnetic means, and mechanical means operative to move said resilient means away from said first mentioned means to render the magnetic means operative, substantially as described. 110

In testimony whereof I have signed my name to this specification in the presence of two subscribing witnesses.
